[57] ABSTRACT

A continuous rotary press is disclosed which essentially comprises a rotary turret rotatable about a drive shaft, a pair of cam grooves stationarily held in position by a press bench and a plurality of dies and the corresponding number of punches cooperative with the respective dies. The dies and punches are radially outwardly slidably carried by the rotary turret and successively move, guided by the respective cam grooves, toward and away from each other during rotation of the rotary turret thereby performing press work.

CONTINUOUS ROTARY PRESS

The present invention generally relates to a press machine and, more particularly, to a continuous rotary press wherein a plurality of radially arranged sets of dies and punches travel in a circular path and, during each travel through 360°, successively perform any one of such press work as blanking, perforating, forming, drawing, ironing, trimming and so on while the strip stock to be processed thereby is continuously fed between the dies and the punches with no interruption in the advance of the strip stock even during the performance of the press work.

In general, most press machines are capable of varied types of work. In other words, a press in itself is not sufficient as a production machine, but must be provided with dies and punches in cooperation with the dies and, by suitably selecting the proper dies and punches, it can be designed for a certain specific operation. In view of the fact, press machines heretofore available are classified in various ways, e.g., according to the design of frame, according to the method of power-transmission, and according to the purpose of press.

The press machine herein disclosed and according to the present invention is, however, termed as "continuous rotary" press in view of the fact that the strip stock to be processed is continuously fed with no interruption in the advance thereof on one hand and, on the other hand, press work is successively performed by the dies and the counteracting punches in one press machine. This may be possibly classified according to the overall function of the press. This concept of the present invention is claimed to be novel and, therefore, it should be considered the original version of this type of press machine.

So far as the production capacity and the continuous supply of the strip stock are both concerned, a press machine called a nonstop press has been recently developed. Unlike most conventional presses, this nonstop press does not employ a clutch or brake mechanism which must be otherwise serviced frequently because of the repetitive loading and unloading which they undergo. In addition, the nonstop press effectively avoids repetitive severe shock loads on crank shafts and their bearings, so that maintenance is reduced considerably.

Structurally, this nonstop press essentially comprises a so-called floating frame carrying dies thereon. The floating frame is designed so as to move reciprocately in the opposite direction parallel to the direction of advance of the strip stock in one complete cycle of operation. Although the nonstop press has such advantages as mentioned above, the production capacity is limited. This is due to the fact that the reciprocal movement of the floating frame itself, which is relatively heavy, at a relatively high speed substantially equal to the speed of supply or advance of the strip stock tends to produce a great inertia force and, therefore, the higher the speed of supply of the strip stock, the more difficult it is to synchronize the speed of movement of the floating frame with the speed of supply of the strip stock.

Accordingly, an essential object of the present invention is to provide a continuous rotary press capable of rapid production with substantial elimination of the disadvantages and inconveniences inherent in the conventional press machine.

Another important object of the present invention is to provide a continuous rotary press of the type above referred to, wherein press work is successively performed while the strip stock to be processed thereby is continuously fed with no interruption in the advance thereof, and which does not require any clutch or brake action and cranking mechanisms and their associated bearings.

A further object of the present invention is to provide 10 a continuous rotary press of the type above referred to, of which each cycle of operation is smoothly performed without substantially imposing repetitive and/or successive severe shock on any part of the press, so that no noisy vibration is generated and so that maintenance is 15 considerably reduced.

A still further object of the present invention is to provide 20 a continuous rotary press of the type above referred to, which can be manufactured at reasonable cost in an extremely compact size for a press having a comparable production capacity and which does not, therefore, require a relatively large space for installation thereof.

It is a related object of the present invention to provide 25 a system which is composed of a plurality of continuous rotary presses each being of the type above referred to for making a press line by which blanking, drawing, ironing and trimming are sequentially performed.

According to the present invention, a continuous rotary press machine essentially comprises 30 a plurality of die units and the corresponding number of punch units cooperative with the respective die units. The die units and the punch units are radially outwardly slidably carried by a rotary turret. Relative sliding movement of these die and punch units in the radially outward directions toward to and away from each other is effected during rotation of the rotary turret through respective cam arrangements which efficiently and effectively guide the relative sliding movement thereof. A strip stock to be pressed thereby is continuously fed thereto 35 without interruption in its advance during the performance of the press work.

The turret can be rotated at a relatively high speed, 40 for example, more than 150 r.p.m., and the machine of the present invention can be capable of rapid production, since the actual time of operation is only the time necessary for the rotary turret to rotate through an angle which is substantially equal to the quotient of the angle of each rotation of the turret divided by the number of the pairs of the die and punch units if a single set of die and punch are respectively provided in the die unit and punch unit.

These and other objects and features of the present 45 invention will become apparent from the following description taken in conjunction with preferred embodiments thereof with reference to the accompanying drawings, in which;

FIG. 1 illustrate how a plurality of cup-shaped cylinders are formed by the press machine of the present invention from a continuous strip material, wherein FIG. 1A is a top plan view of a portion of the strip material, FIG. 1B is a top plan view of a portion of the strip material after having been subjected to a blanking operation, FIG. 1C is a side sectional view of a portion of the strip material after having been subjected to a drawing operation, FIG. 1D is a side sectional view of a portion of the strip material after having been subjected to an

ironing operation and FIG. 1E is a side sectional view of a portion of the strip material after having been subjected to a trimming operation,

FIG. 2 is a perspective view of a continuous rotary press according to the present invention showing an outer appearance thereof,

FIG. 3 is a front view of FIG. 2,

FIG. 4 is a top plan view of the continuous rotary press machine of FIG. 2,

FIG. 5 is a longitudinal sectional view of the continuous rotary press machine,

FIG. 6 is a longitudinal sectional view of an essential portion of the press machine,

FIG. 7 is a longitudinal sectional view of each one of die and punch units, showing the details thereof,

FIG. 8 is a front elevational view of a portion of the press machine, showing only two of the radially outwardly arranged die and punch units with respect to the axis of rotation of a drive shaft,

FIG. 9 is a perspective view of stripper plates employed in the press machine,

FIG. 10 is a longitudinal sectional view, on an enlarged scale, of a portion of FIG. 6, showing a manner by which a cam follower is engaged in a cam groove,

FIG. 11 is a cross sectional view taken along the line XI—XI in FIG. 5,

FIG. 12 is a cross sectional view taken along the line XII—XII in FIG. 5,

FIG. 13 is a cross sectional view taken along the line XIII—XIII in FIG. 11,

FIG. 15 is a side sectional view of the clutch operating mechanism of FIG. 14,

FIG. 16 is a front elevational view of a tensioning unit employed in the press machine of the present invention,

FIG. 17 is a cross sectional view taken along the line XVII—XVII in FIG. 16,

FIG. 18 is a cross sectional view taken along the line XVIII—XVIII in FIG. 17,

FIG. 19 is a front elevational view of a guide, unit employed in the press machine of the present invention,

FIG. 20 is a side elevational view of FIG. 19,

FIG. 21 is a front elevational view of a take-up unit employed in the press machine of the present invention,

FIG. 22 is a cross sectional view taken along the line XXII—XXII in FIG. 21,

FIG. 23 is a longitudinal sectional view of an intermediate transmission mechanism for transmitting a rotational power of a motor to the take-up unit, which is employed in the press machine of the present invention,

FIG. 24 is a similar view of FIG. 6, but differ therefrom in that the die unit is provided with a strip stock depressor while the machine itself is designed to perform a trimming operation,

FIG. 25 is a longitudinal sectional view, on an enlarged scale, of an essential portion of FIG. 25,

FIG. 26 is a longitudinal sectional view of a die and punch arrangement according to another embodiment of the present invention,

FIG. 27 is a longitudinal sectional view of the press machine wherein a different type of positioning unit is provided,

FIG. 28 is an end sectional view taken along the line XXVIII—XXVIII in FIG. 27,

FIG. 29 is a diagram showing an arrangement of cam grooves employed in the press machine of the present invention, which are intended for drawing operation,

FIG. 30 is a chart showing respective traces of dies and punches during rotation of the turret according to the cam groove arrangement of FIG. 29,

FIG. 31 is a diagram showing relative positions of the die and punch units resulting from the cam groove arrangement of FIG. 29,

FIG. 32 is a diagram showing an arrangement of cam grooves employed in the press machine of the present invention, which are intended for ironing operation,

FIG. 33 is a chart showing respective traces of dies and punches during rotation of the turret according to the cam groove arrangement of FIG. 32,

FIG. 34 is a diagram showing relative positions of the die and punch units resulting from the cam groove arrangement of FIG. 32,

FIG. 35 is a diagram showing an arrangement of cam grooves employed in the press machine of the present invention, which are intended for trimming operation,

FIG. 36 is a chart showing respective trace of dies and punches during rotation of the turret according to the cam groove arrangement of FIG. 35,

FIG. 37 is a diagram showing relative positions of the die and punch units resulting from the cam groove arrangement of FIG. 35,

FIG. 38 is a schematic diagram showing a press line composed of a plurality of continuous rotary machines each constructed according to the present invention, and

FIG. 39 is a schematic perspective diagram showing the press line composed of a plurality of the press machines which are housed in respective housing structures.

Before the description of the present invention proceeds, it is to be noted that like parts are designated by like reference numerals throughout the accompanying drawings. It is also to be noted that, although a continuous rotary press according to the present invention can be better adapted to perform any of the various types of press work depending upon the type of dies and punches employed, the description of the present invention will be, so far as the general structural features of the continuous rotary press are concerned, made for the sake of clarification in connection with the rotary press equipped with dies and punches specifically designed for the drawing operation.

However, FIG. 1 illustrates how finished cupshaped cylinders, shown by 5 in FIG. 1E and each satisfying the desired dimensional requirements, are formed from a continuous strip material shown by 1 in FIG. 1A. In order to sequentially perform different processes represented by FIG. 1B to FIG. 1E, i.e., punching, drawing, ironing and trimming, respectively, four continuous rotary presses are required which may be of the same construction, but must be equipped with different types of dies and punches specifically designed for these processes. This fact is well understood by those skilled in the art.

Referring still to FIG. 1, so far as production of cupshaped cylinders 5 is concerned, employment of the punching process represented by FIG. 1B is recommended by the reason well understood by those skilled in the art, though it may be omitted regardless of what-

ever type of press is used. In any event, if employed, the punching process is intended to form equidistantly spaced bases 2, each having a substantial shape similar to the cross section of the finished cupshaped cylinder 5 and linked by a pair of bridges 3 which have been the opposed lengthwise edges of the strip material 1, said bases 2 being naturally situated between each pair of adjacent punched openings 4. The strip material thus shaped as shown in FIG. 1B will be, for the sake of convenience, referred to as a strip stock.

The drawing process represented in FIG. 1C is preferably employed for pre-fabricating cups 5a to prevent stresses from exceeding the elastic limit strength of the metal, i.e., the stock, which may otherwise result in a development of cracks in the strip stock. Excess of the stresses over the elastic limit strength of the metal is particularly considerable if each cup-shaped cylinder having a substantial length is to be produced as shown in FIG. 1D or E. This is true of the press work performed by any type of other presses than that of the present invention. It is to be noted that the only difference between the drawing and the ironing results from employment of different types of dies and punches while the press machines for these processes remain the same.

Ironing and trimming operations may be both performed on one continuous rotary press if a particular type of die and punch designed to iron and trim the cupshaped cylinders 5a and 5 simultaneously, are employed.

From the foregoing, it will be clearly understood by those skilled in the art that the continuous rotary press machine according to the present invention has such a versatility as to make it possible to use the same press for many different jobs and operations.

As regards the details of the continuous rotary press according to the present invention, reference is first made to FIGS. 2 to 8. The continuous rotary press machine constructed according to the present invention essentially comprises a substantially circular framework 10 which may be integrally formed with a press bench 11 by a metal casting technique. The circular framework 10 is integrally formed with an annular flanged portion 10a frontwardly projecting therefrom at right angles to the plane of the framework 10. This framework 10 is also formed at a substantially central portion with an opening which supports a turret 12 and a drive shaft 13 in such a manner as will be hereinafter described.

The turret 12 has a substantially funnel-shaped cross section as shown in FIG. 5 and is integrally formed with a stem 12a which loosely extends through the opening of the framework 10. This turret 12 is rigidly mounted on the drive shaft 13 with the stem 12a rigidly connected thereto, for example, by means of a key-groove engagement or by the use of one or more set pins, so that said turret 12 can rotate together with the drive shaft 13. As best shown in FIGS. 5 and 6, a ball bearing 14 of a type composed of a plurality of balls and a pair of outer and inner rings 14a and 14b with said balls rollably situated therebetween is mounted on the stem 12a of the turret 12 at the central opening of the framework 10 for facilitating a smooth rotation of the turret 12 relative to the framework 10. This ball bearing 14 is secured in position in such a manner that bolts are tapped into the framework 10 as at 15 through a radially outwardly extending flange, integrally formed with the

outer ring 14a, while a set ring 16 is threaded to a free end of the stem 12a so as to avoid a possible displacement of the inner ring 14b.

The turret 12 is formed as at 17 with a plurality of 5 pairs of first slide bores radially outwardly extending at right angles to the longitudinal axis of the drive shaft 13 and is also formed as at 18 with the corresponding number of second slide bores situated backwardly of said individual pairs of first slide bores 17 and in parallel to the latter and similarly radially outwardly extending at right angles to the longitudinal axis of the drive shaft 13. As best shown in FIG. 6, each of the first slide bores 17 and each of the second slide bores 18 are both provided with bushings 17a and 18a, respectively, 15 which are non-detachably inserted in said slide bores 17 and 18.

An annular cam plate 19 having a cam groove 19a formed therein of a configuration as will be described later is rigidly, or otherwise integrally, secured to the 20 annular flanged portion 10a of the framework 10. Similarly, another annular cam plate of a smaller size than the cam plate 19, which has a cam groove 20a formed therein of a configuration as will be described later, is supported by the framework 10 through a positioning 25 unit 21 of a construction as will be described later.

In the above construction, the continuous rotary press machine further comprises die units and punch units, each being provided in a number of substantially equal to the number of pairs of the first slide bores 17 30 or the number of the second slide bores 18. Because these die units and these punch units are individually of the same construction, only one each of the die units and the punch units will be described for the sake of facilitating a better understanding thereof.

35 Each die unit and the punch unit associated therewith are best shown in FIGS. 6 to 8 and generally indicated by 22 and 23, respectively.

The die unit 22 comprises a pair of shanks 24 slidably extending through the bushings 17a in said first slide bores 17, respectively, in parallel and spaced relation with respect to each other. Individual first ends of these shanks 24 are rigidly connected by set pins 25 with a bracket 26 which carries an eccentric cam follower 27 in a manner as hereinafter described. With particular reference to FIG. 10, a shaft 28 extends through the bracket 26 and has one end eccentrically mounted, or otherwise integrally formed, with said cam follower 27 with a spacer or washer 29 interposed between said bracket 26 and said cam follower 27. The other end of the shaft 28 is threaded to receive a nut 30 rigidly screwed thereto. It is to be noted that, although the cam follower 27 slidably engages in the cam groove 19a of the cam plate 19 without rotating about the longitudinal axis of the shaft 28, this eccentric mounting of the cam follower 27 on the shaft 28 permits the relative position of the die unit 22 with respect to the associated punch unit 23 to be finely adjusted during the course of assembly of the press machine. However, this eccentric mounting is not always necessary and the cam follower 27 may be in the form of a roller coaxially rotatably mounted on the shaft 28.

60 The second individual ends of the shanks 24 opposed to the above mentioned first ends thereof are connected to each other by and mounted with a spacer block 31 formed with an opening as at 31a. For this purpose, a pair of bolts, generally indicated by 32, extend through said spacer block 31 and are then tapped

into the respective shanks 24 as best shown in FIG. 6.

Secured to the spacer block 31 by means of a plurality of bolts 33 is a carriage 34, the details of which are best shown in FIG. 7. As shown, this carriage 33 is formed with a pair of guide holes 34a and also with a pair of recesses 34b of circular cross section situated on one end face thereof adjacent to the shanks 24. This carriage 34 is also formed with through holes 34c respectively in alignment with said recesses 34b. A die holder 35 having longitudinally extending holes 35a formed therein and sleeve-shaped dies 36 respectively non-detachably inserted in said holes 35a is secured to the carriage 34, with the dies 36 aligned respectively with the through holes 34c, by the use of bolts 37 which extend through the carriage 34 and are then tapped into the die holder 35. For facilitating positioning of the die holder 35 relative to the carriage 34 prior to screwing of the bolts 37 and/or during replacement of the dies 36 of different types, one or more alignment pins 38, each having one end pressure fitted into either the carriage 34 or the die holder 35 and the other end engaged into the holder 35 or the carriage 34, are provided.

The recesses 34b in the carriage 34 are closed by individual caps 39 mounted on the other end face of said carriage 34 by the use of, for example, set screws (not shown). Knock-out pins 40 each having a flat land 40a integrally formed therewith slidably extend through the holes 34c and then the dies 36 while the flat lands 40a thereof are situated within the recesses 34b. These knock-out pins 40 are biased towards the punch units 23 with the respective flat lands 40a resting on the bottoms of these recesses 34b by the action of compression springs 41 each interposed between the cap 39 and the flat land 40a of the knock-out pin 40, and within the recesses 34b, respectively. As will become clear, each knock-out pin 40 acts to eject a drawn cup on the strip stock to avoid a possible clog of the corresponding die 36.

Still with particular reference to FIGS. 5 to 8, each punch unit 23 comprises a carriage 42 of substantially L-shape as shown, which carries guide posts 43 pressure fitted thereto for sliding engagement in the respective guide holes 34a in the die carriage 34 during relative motion of these die and punch units 22 and 23, as will be described later, so as to guide this relative motion. As best shown in FIG. 6, this punch carriage 42 is rigidly secured to a sliding block 44 by a bolt 45 extending therethrough and tapped into said sliding block 44. An alignment member 46 having one end tapped into the sliding block 44 and the other end slidably engaged in a guide groove formed in said block 44 as at 44a is provided for avoiding an arbitrary pivot of the block 44 about the axis of the bolt 45. The sliding block 44 thus carrying the punch carriage 42 is positioned so as to be backed up by the turret 12 with the intervention of a plate member rigidly secured as at 47 to the turret 12 by a plurality of set screws 48 tapped into the turret 12, thereby to provide no substantial frictional resistance to the movement of the sliding block 44. If that portion of the turret 12 where the plate member 47 contacts is polished to provide a smooth surface, the plate member 47 that has been described as employed in this instance may be, of course, omitted. This sliding block 44 is rigidly connected through a shank 49 with a cam follower 50, slidably engaged in the cam groove

20a in the cam plate 20, in a manner as will be now described.

The shank 49 is connected with the sliding block 44 in any suitable method and, in the instance as shown, 5 has one end inserted in said block 44 and is then held in position by a set pin 51 extending through the block 44 across shank 49, a substantially intermediate portion of which slidably extends through the bushing 18a within the second slide bore 18 in the turret 12. 10 The other end of said shank 49 is mounted with a substantially L-shaped bracket 52 carrying said cam follower 50, said bracket 52 being rigidly secured thereto by a nut 55 fastened to the end extremity of said shank 49. Mounting of the cam follower 50 relative to the 15 bracket 52 is substantially the same as that of the cam follower 27 relative to the bracket 26 and, therefore, will not be described for the sake of brevity.

It is to be noted, however, that the plate member 47 may be in the form of an annular ring plate common to 20 all the blocks 44 of the radially arranged, individual punch units 22 as shown in FIGS. 2 and 3.

Each carriage 42 of the punch units 22 is, as best shown in FIG. 7, mounted with a pair of punches 54 in 25 position to respectively align with the dies 36. A punch holder 55 is rigidly mounted on the carriage 42 by a plurality of bolts 56 so that these punches 54 are held in position in respective alignment with the dies 36 and to substantially extend at right angles to the longitudinal axis of the drive shaft 13. It is to be noted that, in 30 the instance as shown, the punches 54 are shown in the form of drawing punches for use in drawing operation. However, when trimming punches are to be used, replacement can be easily performed merely by undoing the bolts 56.

35 The punch unit 23 further comprises a polygonally shaped block 57 having flat flanks 57a in a number corresponding to the number of the die units 22, for example, 12 flat flanks in the instance as shown in FIGS. 2 and 3. This polygonally shaped block 57 is rigidly 40 mounted on the shaft 13 for rotation together with said drive shaft 13 in such a way that the flanks 57a face towards the respective die units 22. Mounting of the polygonal block 57 on the drive shaft 13 is preferably carried 45 out by a key and groove engagement (not shown) and a fastening nut 58 is used for avoiding separation of the block 57 from the drive shaft 13.

Stripper plates 59, each having guide openings formed as at 59a and sleeves 60, non-detachably inserted respectively in said guide openings 59a are rigidly mounted on the flat flanks 57a of the block 57 by means of a plurality of set bolts, extending therethrough and tapped into the block 57 as at 61, with each pair of the sleeves 60 in alignment with and in 55 spaced relation to the punches 54 carried by the associated carriage 42. As shown in FIGS. 8 and 9, each of the stripper plates 59 is so shaped that the outer appearance of the arrangement of these plates 59 mounted on the block 57 represents an contour similar to the polygonal shape of said block 57.

60 As best shown in FIGS. 7 and 9, each stripper plate 59 may be provided, as at 62, with a pair of positioning pieces extending in equidistantly spaced relation to each other on both sides of an imaginary line passing through the centers of the sleeves 60. These positioning pieces 62, if employed, act to avoid displacement of the strip stock with respect to the direction of advance of 65 said strip stock. In addition, a locating piece 63 may be,

as shown in FIG. 9, provided on each stripper plate 59, either singly or in combination with the positioning pieces 62, particularly in the case where the strip stock already shaped as shown in FIG. 1B is subjected to the drawing operation. The provision of the locating piece 63 on each stripper plate 59 brings an advantage in that, in view of the fact that it is positioned so as to engage in any one of the punched openings 4 of the strip stock 1, each base 2 of the strip stock 1 can be not only exactly aligned with the die and punch, but also held in position during the continuous advance of said strip stock.

Although in the foregoing description each die unit 22 and its associated punch unit 23 have been described as provided with pairs of dies 36 and punches 54, respectively, the number thereof per die unit 22 and punch unit 23 is not limited thereto. A single die 36 may be sufficient and this notion shall apply to the associated punch 54. Similarly, a single shank 24 may be sufficiently employed instead of the two shanks described above.

Reference numeral 64 represents a spacer sleeve mounted on the drive shaft 13 between the polygonal block 57 and the turret 12, which may be omitted if desired.

Hereinafter, the details of the drive system for rotating the drive shaft 13 and, hence, the turret 12 about the longitudinal axis of said drive shaft 13 will be described with particular reference to FIGS. 4, 5, 14 and 15. The drive system includes a clutch unit 65 for selectively transmitting a rotational force originating from the motor M to said drive shaft 13. The clutch unit 65 includes a clutch sleeve 66 having one end rigidly connected with an intermediate shaft 67, extending from a reduction gear unit 68 of any known construction, and the other end formed with an annular clutch plate 66a. This clutch sleeve 66 is independently rotatably mounted on the drive shaft 13 through suitable bearings 69 and rotatably carried by a suitable bearing box 70 supported in position on the press bench 11. The clutch unit 65 further includes a counteracting clutch plate 71 mounted on the shaft 13 by means of a key and groove engagement as indicated by 72 for movement in the axial direction of the drive shaft 13, said counteracting clutch plate 71 being selectively engageable and disengageable with respect to the clutch plate 66a in a manner as will be hereinafter described. However, it is to be noted that engagement faces of both of the clutch plates 66a and 71 are in practice suitably shaped to match each other for the purpose of transmitting the whole rotational force from the intermediate shaft 67 to the drive shaft 13.

As best shown in FIGS. 14 and 15, an operating rod 73 having both ends suitably journaled by the press bench 11 at the opposite positions extends transversely of the drive shaft 13 and below said drive shaft 13. One of these ends of said operating rod 73 is connected with a pivotal block 74 by a set pin 75, said pivotal block 74 carrying a handle 76. The handle 76 has one end pivotally connected with a detent pin 77 which extends through said pivotal block 74 and is selectively engageable in a detent recess 11a formed in the press bench 11. The other end of said handle 76 is formed into an operating knob 76a, a substantially intermediate portion thereof being pivotally supported by the pivotal block 74 by means of a pin member 78. A tension spring 79 is suspended between said pivotal block 74

and said handle 76 so that said handle 76 is biased about the axis of the pin member 78 with the detent pin 77 tending to engage in said detent recess 11a. The pivotal block is pivotable between two positions, one 5 being represented by the detent recess 11a, about the axis of the operating rod 73, if an external pushing force is applied to the handle 76. It should be understood that another detent recess similar to the recess 11a is provided in the press bench 11 at the other position 10 of movement of the pivotal block 74. Engagement of the detent pin 77 into the other detent recess (not shown) can be effected by pivoting the pivotal block 74 about the axis of the operating rod 73 while the handle 76 is, if the detent pin 77 is at this time engaged in the 15 detent recess 11a, pivoted about the axis of the pin member 78 against the tension spring 79 so as to disengage said detent pin 77 from said detent recess 11a.

The operating rod 73 has a substantially intermediate portion mounted with a fork member 80 having a pair 20 of finger portions generally indicated by 80a. This fork member 80 is mounted on said operating rod 73 by means of a key and groove engagement 81 and carries a pair of rollers 82 respectively rotatably secured to the tip portions of said finger portions 80a and rotatably 25 engaged in an annular groove which is formed on the counteracting clutch plate 71 as at 82 (FIG. 5).

From the foregoing description, it has now become clear that, depending upon the position of the handle 76, the clutch plate 71 can be selectively moved toward 30 and away from the clutch plate 66a respectively for transmitting the rotational force of the intermediate shaft 67 to said drive shaft 13 and interrupting such transmission.

In any event, the clutch unit 65 is not a subject matter 35 of the present invention and, therefore, any type of known clutch mechanisms may be effectively employed.

As shown in FIGS. 4 and 5, the motor M is operatively connected with the reduction gear unit 68 by 40 means of an endless belt 83 which is in turn connected with the intermediate shaft 67 so that a rotational force exerted by said motor M can be effectively transmitted to said intermediate shaft 67. However, it is to be noted that, in the case where the single motor M is to be used 45 to operate a plurality of the continuous rotary press machines according to the present invention, a length of driven shaft 84 may be used as shown in FIG. 4 which extends through the corresponding number of reduction gear units and which carries a single pulley 50 85 around which the belt 83 is suspended.

In the arrangement so far described, it is clear that rotation of the drive shaft 13 accompanies the corresponding rotation of both of the die units 22 and the 55 punch units 23 about the axis of said drive shaft 13. During this rotation, depending upon the individual configurations of the cam grooves 19a and 20a respectively formed in the cam plates 19 and 20, the die units 22 and punch units 23 undergo successive relative motion toward and away from each other in the opposite 60 directions with the cam followers 27 and 50 slidingly guided in the cam grooves 19a and 20a thereby to perform successive press work.

FIGS. 16 to 18 illustrate tensioning unit 86 arranged in position as shown in FIGS. 2 to 4 by means of a support plate 87 rigidly secured to the press bench 11. The tensioning unit 86 comprises two pairs of rollers 88 and 65 89, 90 and 91 rotatably supported by the support plate

87 in a manner as will be now described. As clearly shown, the roller 88 is rotatably mounted on a spindle 92, rigidly carried by said support plate 87, with a spacer sleeve 93 mounted on the spindle 92 between said roller 88 and said support plate 87. This roller 88 is formed on its outer periphery with a pair of spaced flanges 88a as shown. On the other hand, the roller 89 is supported to the support plate 87 in a substantially similar manner as said roller 88 and, therefore, the details thereof are herein omitted. However, it is to be noted that the roller 89 is formed on its outer periphery with a pair of spaced flanges 89a, the space between said flanges 89a being greater than the space between the flanges 88a of the roller 88, and is positioned below the roller 88 with the space between the flanges 89a receiving therein the flanges 88a of the roller 88. This pair of rollers 88 and 89 merely serve to carry the strip stock 1 on the trailing side with respect to the direction of advance of the strip stock 1.

The other pair of rollers 90 and 91 are disposed on the leading side of the direction of advance of the strip stock 1 and used to apply a tension to said strip stock in cooperation with each other. For this purpose, the roller 90 is of a similar shape to the roller 88, having a pair of spaced flanges 90a on its periphery and is, as best shown in FIG. 16, rotatably carried by a pivotal lever 94 having one end rigidly connected with a spindle 95 on which said roller 90 is mounted and the other end pivotally secured to the support plate 86 by means of a bolt 96 and a nut 97 fastened to said bolt 96.

The roller 91 is supported in such a manner as follows. A spindle 98 having a sufficient length has one end secured to the support plate 86 by means of a nut and the other end threaded to receive an adjustment knob 100. As best shown in FIG. 18, the roller 91 is of similar shape to the roller 89, having a pair of spaced flanges 91a, and is rotatably mounted on a substantially intermediate portion of the spindle 98 with the space between said flanges 91a receiving therein the flanges 90a of the roller 90 positioned above said roller 91. Interposed between the roller 91 and the support plate 87 is a spacer sleeve 101 mounted on said spindle 98. While in this arrangement, a compression spring 102 and a friction ring 103 are disposed between the adjustment knob 100 and mounted on the spindle 98 at the other end portion thereof. The friction ring 103 is rigidly secured to the spindle 98 in that position by means of a key and groove engagement as indicated by 104, but is capable of axial sliding movement in parallel to the longitudinal axis of the spindle 98. A contact force exerted between the roller 91 and the friction ring 104 can be adjusted by the resiliency of the compression spring 102 which is in turn adjusted by turning the adjustment knob 100. A bolt 105 threadably inserted in the adjustment knob 100 in the longitudinal direction of the knob 100 is used to secure the adjustment knob 100 in position thereby to avoid an accidental loosening of the adjustment knob 100 during operation of the press machine.

The pivotal lever 94 is biased about the axis of the bolt 96 by a tension spring 106, suspended between an arm 94a integral with said lever 94 and the support plate 87 as at 87a, whereby said roller 90 is pressed to the roller 91 through the flanges 90a. In practice, the strip stock having cups 5a formed in a row as shown in FIG. 1C is held by the pair of the rollers 90 and 91 in such a way that the opposed bridges 3 are sandwiched

under pressure between the flanges 90a and a portion of the periphery of the roller 91 which is situated within the space between the flanges 91a while the cups 5a are situated within the space between the flanges 90a.

5 The tension given to the strip stock between said tensioning unit 86 and the press section, i.e., the polygonal block 57, can be easily adjusted by turning the adjustment knob 100 at the operator's will and also by suitably selecting the resiliency of the compression spring 106, or by adjusting the adjustment knob 100 in reference to the selected resiliency of the compression spring 106.

FIGS. 19 and 20 illustrate a guide unit by which the strip stock can be effectively guided so as to travel 15 around the stripper plates 59 circumferentially arranged round the drive shaft 13. This guide unit generally indicated by 107 comprises a support 108 secured to the press bench 11 through at least one pair of spaced legs 109, and a pair of guide rails 110a and 20 110b, each supported by the support 108 by means of at least one pair of arms 111a and 111b or 112a and 112b in such a manner as hereinafter described.

The guide rail 110a of a channel shaped cross section has one end portion supported by the arm 111a and the 25 other end portion supported by the arm 111b, a substantially intermediate portion thereof being curved, and extends in a slightly twisted manner so that the exit side 110c of said rail 110a is situated immediately above the stripper plates 59 between each die unit 22 and 30 its associated punch unit 23 while the entrance side 110d faces towards the tensioning unit 86 situated frontwardly of the plane of rotation of the turret 12 as shown in FIGS. 2 and 3. On the other hand, the guide rail 110b, of the same construction as the guide rail 110a, has one end portion supported by the arm 112a and the other end portion supported by the arm 112b, a substantially intermediate portion thereof being situated above the guide rail 110a and bridging thereover. Even this guide rail 110b extends in a slightly twisted 35 and curved manner so that the entrance side of said rail 110b, as shown at 110e, is situated immediately above the stripper plates 59 between each die unit 22 and its associated punch unit 23 while the exit side 110f thereof faces towards a take-up unit 113 situated frontwardly of the plane of rotation of a turret 12 as shown in FIGS. 2 and 3 and of the construction as will be described later.

In the above construction of the guide unit, the strip stock 1 between the tensioning unit 86 and the take-up 50 unit 113 travels in a substantially spiral form around and in contact with the stripper plates 59 while a portion of said strip stock contacting the stripper plate 59 is guided within the spaced positioning pieces 62.

The take-up unit 113 is illustrated particularly in 55 FIGS. 21 to 23. Referring now to these drawings, the take-up unit 113 comprises a support plate 114 rigidly secured to the press bench 11 as shown in FIGS. 2 to 4 and formed with an opening as at 114a. The support plate 114 rigidly carries a bearing box, generally indicated by 115 and secured to one side of said support plate 114 in alignment with said opening 114a. Axially non-movably extending through the opening 114a and the bearing box 115 is a shaft 116 having one end adjacent to said bearing box 115 rigidly mounted with a driven pulley 117, which is connected with the motor M in such a manner as will be described later, and the other end threaded to receive an adjustment knob 118

adjustably mounted thereon. Between the support plate 114 and the adjustment knob 118, a spacer sleeve 119, a roller 120, a friction ring 121 and a compression spring 122 are respectively mounted on the shaft 116 in the order given above. The roller 120 is rotatable about its own rotational axis independently of rotation of the shaft 116, but can receive a rotational force of the shaft 116 in a manner as will be now described.

The friction ring 121, formed on its periphery with a circumferentially extending groove 121a, is engaged on the shaft 116 by means of a key and groove engagement as at 123 for rotation together with said shaft 116. As best shown in FIG. 22, the compression spring 122 is so suspended on the shaft 116 and between the adjustment knob 118 and the friction ring 121 that the latter is pressed towards the roller 120. Therefore, it is clear that the rotation of the shaft 116 accompanies the corresponding rotation of the friction ring 121, a rotational force of which is then transmitted to the roller 120 through the frictional engagement between said friction ring 121 and said roller 120. The contact pressure exerted between said friction ring 121 and said roller 120 can be advantageously adjusted merely by turning the adjustment knob 118, the latter being capable of being fixed at a definite position on the shaft 116 by fastening a bolt 124 which is arranged in a substantially similar manner as the bolt 105 in the tensioning unit 86.

The roller 120 is formed on its periphery with a pair of spaced flanges 120a, the space therebetween corresponding to the width of the strip stock 1 used.

A presser roller 125 having its periphery formed with a pair of spaced flanges 125a and a groove as at 125b is rotatably and axially non-movably mounted on a stud 126 rigidly carried by a pivotal lever 127 which is in turn pivotally secured to the support plate 114 by means of a bolt 128 and a nut (not shown) fastened to said bolt 128. A tension spring 129 has one end connected with the pivotal lever 127 and the other end connected with the support plate 114 in such a way as to bias said lever 127 about the axis of the bolt 128 in one direction with the presser roller 125 contacting the roller 120 through the flanges 125a engaging in the space between the flanges 120a of the roller 120.

An endless belt 130 is suspended between the groove 125b on the roller 125 and the groove 121a on the friction ring 121 for positively rotating said presser roller 125 in a direction counter to the rotational direction of the friction ring 121 and, hence, the shaft 116. This endless belt 130 and the grooves 121a and 125b are not always necessary and, therefore, they may be omitted if the tension spring 129 sufficiently serves to cause the presser roller 125 to engage the roller 120 with the strip stock 1 sandwiched therebetween without incurring any slip thereat.

An intermediate transmission mechanism for transmitting the rotation of the drive shaft 84 (FIG. 4) to the pulley 117 through an intermediate shaft 140 rotatably supported by the press bench 11 as at 131 in FIG. 4 is shown in FIGS. 5 and 23 by 132. This intermediate transmission mechanism 132 comprises a support plate 133 rigidly secured to the press bench 11 and formed with an opening 133a. A shaft 134 rotatably extends through said opening 133a in said support plate 133 and has one end mounted with a pulley 135 and a bevel gear 136, both for rotation together with said shaft 134, and the other end thereof journalled by a bearing box 137 rigidly secured to the support plate 133.

The pulley 135 is connected with the pulley 117 on the shaft 116 by an endless belt 138 suspended therebetween.

As shown in FIGS. 4 and 5, the bevel gear 136 on the shaft 134 is constantly engaged with a counteracting bevel gear 139 rigidly mounted in position on the intermediate shaft 140 which has one end carrying said counteracting bevel gear 139 and the other end carrying an intermediate pulley 141. An endless belt 142 is suspended between said pulley 141 and a pulley 143, rigidly mounted on the shaft 84, whereby rotation of said shaft 84 caused by the motor M is effectively transmitted to the pulley 117 through the intermediate transmission mechanism 132.

It is to be noted that, as shown in FIG. 4, the motor M may be coupled with a clutch brake 144 which may be in turn connected with the shaft 84 through the endless belt 83.

The positioning unit 21 shown in FIGS. 5 and 6 is shown in detail in FIGS. 11 to 13. This positioning unit 21 is not always necessary and, however, if provided as is the case in the embodiment shown, it functions to adjust the position of the cam plate 20 in circumferential and/or radial directions with respect to the axis of rotation of the turret 12.

Referring now to FIGS. 11 to 13, the positioning unit 21 comprises a pair of blocks 145 rigidly secured to one face of the cam plate 20 opposite to the cam groove 20a by a plurality of set screws 146 in a spaced relation 30 with respect to each other. These blocks 145 are, as best shown in FIG. 11, positioned in symmetrical arrangement with respect to the axis of the drive shaft 13 and aligned in a diagonal direction with respect to the contour of the flanged portion 10a of the framework 10. The cam plate 20 is diagonally movable with the blocks 145 slidably guided by respective pairs of guide pieces, generally indicated by 147. Said guide pieces 147 of each pair are disposed on both sides of the corresponding block 145 as shown and rigidly secured in position to an annular plate 148 by a plurality of set screws as at 149. The annular plate 148 is in turn carried by the framework 10, in a manner as will be described later, for rotation about the axis of the shaft 13 through a predetermined angle. Two pairs of set bolts 45 150 respectively extend through short slots 148a, formed in the annular plate 148, and are then tapped into the corresponding blocks 145, each of said short slot 148a extending in parallel to the direction of sliding of the blocks 145 and, hence, the annular cam plate 20, whereby the stroke of linear movement of said cam plate 20 is defined by the length of the slots 148a.

The framework 10 is formed as at 10b with a pair of long slots within which head portions of the set bolts 150 of each pair are loosely situated. As shown in FIG. 512, this framework 10 is also formed as at 10c with a plurality of slots each equidistantly spaced from the axis of the drive shaft 13. The corresponding number of set bolts 152 extend through the respective slots 10c and are tapped into the annular plate 148 as seen from FIG. 13.

As best shown in FIG. 11, an adjustment spindle 153 extends through a slot 10d and threadably tapped into one of the blocks 145 so that manual rotation of said adjustment spindle 153 may cause the cam plate 20 to move in the diagonal direction. In other words, merely by turning the adjustment spindle 153, the positioning relation of the cam plate 20 with respect to the drive

shaft 13 can be easily adjusted. In addition, since the slot 10d formed in the flanged portion 10a of the framework 10 extends in parallel to the plane of rotation of the annular plate 148, movement of said spindle 153 in the lengthwise direction of said slot 10d causes the cam plate 20 to rotate about the axis of the shaft 13 in an angular distance defined by the length of each of the slots 10c in cooperation with the set bolts 150.

FIGS. 24 and 25 illustrates a modification required for the press machine to be used the trimming operation. As hereinbefore described with reference to FIG. 1, the trimming operation is intended to trim the cup-shaped cylinders 5 arranged in a row on the strip stock 1 and already processed in the preceding drawing operation. In this case, means is required in the press machine for discharging the trimmed cylinders from the strip stock into a suitable receptacle or container positioned outside the press machine. For this purpose, tubings 154 for each die carriage 34, each being of an inner diameter slightly greater than the diameter of each cupshaped cylinder 5, are provided. Each die carriage 34 does not include the knock-out pins 40 and its associated parts such as compression springs 41 and caps 39 and, instead thereof, ends of the tubing 154 are connected to the openings 31a of the spacer block 31 in alignment with the dies 36 through the recesses 34b of the carriage 34, respectively. These tubings 154 in turn extend in parallel to each other and also to each shank 24 and terminate at a position within and adjacent to a stationary chute 155 of channel-shaped cross section. As schematically illustrated in FIG. 37, the stationary chute 155 is curved and extends between two positions; one where the cup-shaped cylinders that have been successively trimmed and impelled radially outwards through the tubings 154 under the influence of centrifugal force exerted by continuous rotation of the turret 12 are received thereby and the other position is where the trimmed cylinders 5 received by said chute 155 are discharged into a suitable container (not shown) through a belt conveyor 156 shown in FIGS. 38 and 39 which extends between said container and said chute 155 below the rotary turret 12.

A bridge depressor 157 is also provided as shown in FIGS. 24 and 25. This bridge depressor 157 includes a pair of legs 158 slidably inserted in passages each composed of openings respectively formed as at 35b and 34c in the die holder and in the die carriage 34 and a recess 31b formed in the spacer block 31. Compression springs 159 are respectively housed within said passages and so disposed as to bias said legs 158 with the depressor 157 close to the stripper plate 59. In operation, as the die holder 35 approaches the stripper plate 59, the depressor 157 contacts said stripper plate 59 thereby to firmly press the bridges 3 of the strip stock against said stripper plate 59, thus ensuring an effective and efficient trimming operation without permitting the strip stock to float from the stripper plate 59. As the die holder 35 further approaches said stripper plate 59 while the turret 12 carrying said die holder 35 is rotated, the depressor 157 is relatively moved, while contacting the stripper plate 59, with the legs 158 collapsed into the respective passages compressing the springs 159.

Each punch 54 for the trimming operation should be understood as having a step as at 54a of a diameter substantially equal to the inner diameter of the die 36. This step 54a cooperates with the annular inner edge of one

end of the die 36 facing towards said punch 54 for ensuring an accurate and reliable trimming as well known to those skilled in the art.

It is to be noted that firm contact of the strip stock 5 against the stripper plate 59 through the depressor 157 can be easily and reliably ensured as the compression springs 159 are each compressed in the manner as hereinbefore described to accumulate axially acting pushing force.

- 10 In FIG. 26, a modification of each punch unit 23 is illustrated. In this modification, the sleeves 60 are made to be slidable respectively within the guide opening 59a of the stripper plate 59 and biased so as to slightly project outwardly from the plane of the stripper plate 59. For this purpose each compression spring 160 is interposed between the punch holder 55 and one end of the sleeve 60 adjacent said punch holder 55. Slidable mounting of these sleeves 60 is particularly advantageous in that, even if the strip stock has an uneven thickness and/or a rough surface, it can be tightly positioned against the annular end face of the corresponding die 36 so that formation of wrinkles which may otherwise occur at the root of each cup 5a or 5b can be advantageously avoided.
- 15 FIGS. 27 and 28 illustrate another example of the positioning unit 21. In this illustration of FIG. 27, the arrangement of the press machine somewhat differs from that which has been described above. This is because the positioning unit in this example is constructed such as hereinafter described and, hence, it should be understood that, despite this difference, the principle of the press machine in FIG. 27 is substantially the same as that shown in FIGS. 2 to 10 and 14 to 23. Therefore, only the positioning unit embodied in the press machine in FIG. 27 will be now described.
- 20

- 35

In FIG. 27, the cam plate 20 having the cam groove 20a is secured to a disc 161. This disc 161 is integrally formed with a stem portion 161a through which said disc is independently rotatably mounted on the drive shaft 13 by means of bearings as at 162.

Similarly, the cam plate 19 having the cam groove 19a is rigidly secured to an annular support plate 163 which is in turn mounted on the stem portion 161a of the disc 161 through an eccentric ring 164. This annular support plate 163 is supported to the press bench 11 for rotation through a predetermined angle about the axis of the drive shaft 13 and also for movement in a predetermined distance in a transverse direction with respect to said axis of said drive shaft 13. For this purpose, a bracket 165 secured on the press bench 11 is provided with a bolt 166 loosely extending through a slot formed therein and tapped into a portion as at 167 of the cam plate 19.

55 The eccentric ring 164 is shaped as shown in FIG. 28 and, therefore, rotation of either the eccentric ring 164 or the annular support plate 163 about the shaft 13 results in eccentric movement of said support plate 163 and, hence, the cam plate 19 with respect to said shaft 13. By doing this, the relative position of the cam grooves 19a and 20a can be adjusted. An arbitrary rotation of the disc 161 can be prevented by a plurality of bolts 168 which respectively extend through corresponding slots, formed as at 167 in said annular support plate 163, and then tapped into said disc 161. These bolts 168 and the bolt 166 should be firmly fastened after adjustment has been effected in the above described manner.

The contour of each of the cam grooves 19a and 20a and operation of the continuous rotary press machine according to the present invention will be now described with reference to FIGS. 29 to 37. It is, however, to be noted that, strictly speaking, the continuous rotary press according to the present invention may satisfactorily function without the tensioning unit 86 and the take-up unit 113 is a feed reel, around which the unprocessed strip stock is coiled, and a take-up reel around which the processed strip stock, i.e., scrap is wound up are respectively provided in position corresponding to the tensioning and take-up units. In this case, tension can be given to a portion of the strip stock round the polygonal block 57 if frictional resistance is imparted to rotation of either or both of the feed and take-up reels.

In addition, without the take-up unit 113 or the alternative take-up reel being motor-driven, the press machine of the present invention satisfactorily operates because advance of the strip stock can be effected during rotation of the turret 12 while it is sandwiched successively between the die units 22 and the punch units 23.

In view of the foregoing, therefore, the details of operation of the take-up unit 113 and the feed unit 86 are omitted for the sake of brevity, but it should be borne in mind that these units 86 and 113 cooperate with each other to give a suitable tension to the strip stock at a portion between said units 86 and 113.

Referring now to the accompanying drawings, FIGS. 29 to 31 are associated with the drawing operation performed by the press machine of the present invention to form the cups 5a on the strip stock as shown in FIG. 1C. For this drawing operation, the cam grooves 19a and 20a formed in the individual cam plates 19 and 20 are respectively shaped as shown in FIG. 29 so that the press machine follows the mode of operation as represented in a chart of FIG. 30 with the die and punch units 22 and 23 successively conditioned as shown in FIG. 31.

Assuming that the 0° position of the turret 12 rotating about the axis X of the drive shaft 13 located immediately above said axis X and on the imaginary line passing through said axis X in parallel to a vertical line, the relative space between these cam grooves 19a and 20a for the drawing operation are selected such that (1) at position P₁, each die unit 22 commences to approach towards its associated punch unit 23 while contact of the strip stock to the stripper plate 59 included in said associated punch unit 23 has been already achieved during the advance thereof; (2) at position P₂, the punch carriage 42 of said associated punch unit commences, while the strip stock has been completely sandwiched between said die and punch units 22 and 23, to approach the die unit 22 with the punches 54 causing the strip stock to deform inwardly of the corresponding dies 36; (3) at position P₃, the die unit 22 and the punch unit 23 commences, immediately after the drawing has been completed, to relatively separate from each other; and (4) at position P₄, both the die unit 22 and the punch unit 23 complete their respective returns to the original positions.

During the rotation of the turret 12 from the position P₂ to the position P₃, press work is performed in such a way that the punches 54 gradually outwardly project from the level of the stripper plate 59, thus forming the

cups 5a and then retract inwardly of said stripper plate 59.

FIGS. 32 to 34 are associated with the ironing operation to form the cups 5b as shown in FIG. 1D with the die and punch units 22 and 23 successively operating in a manner as represented in a chart of FIG. 33. It is to be noted that, as is well known to those skilled in the art, each of the dies 36 and its associated punch 54 for the ironing operation is selected such that the clearance between said die and punch is slightly smaller than the wall thickness of the cup 5a for the purpose of making the wall thickness thereof uniform at any place. Therefore, as clearly understood from FIGS. 33 and 34, at the position P₂, the punches are substantially completely outwardly projected from the level of the stripper plate 59 while received within the respectively corresponding cups 5b shown in FIG. 1D. During the rotation of the turret 12 from the position P₂ to the position P₃, while the punch unit 23 assumes a position with the punches completely outwardly projected, the die units 22 further approach the associated punch unit 23 with the dies 36 receiving therein the cups 5b supported by the outwardly projected punches 54, i.e., performing the ironing operation, and thereafter the die unit and the punch unit relatively separate from each other.

The relative space of the cam grooves 19a and 20a for the trimming operation is shown in FIG. 35 which is substantially similar to that shown in FIG. 32. However, care must be taken in the design of the cam grooves 19a and 20a so that the step 54a (FIG. 24) of each punch 54 should slightly and outwardly project from the level of the stripper plate 59 during rotation of the turret 12 from position P₂ as shown by the broken line in FIG. 36. It will be, therefore, understood that each die unit 22 and its associated punch unit 23 operate in a manner as substantially shown in FIG. 37.

In any one of the drawing, ironing and trimming operations, the relative motion of the die and punch units 22 and 23 is carried out by the radially inward and outward movement of the shanks 24 and 29, slidably carried by the rotating turret 12, in the opposite directions transverse of the longitudinal axis of the drive shaft 13 while the cam followers 27 and 52 are respectively slidably engaged in the cam grooves 19a and 20a. It is to be noted that, during each rotation of the turret 12 through 360°, any one of the press works is successively performed in times corresponding to the number of pairs of the die units and the punch units. Therefore, the press machine according to the present invention can achieve the production rate per minute which is substantially equal to the product of the number of pairs of the die and punch units times the number of rotations of the turret 12 per minute. This production rate will be doubled if each pair of the die and punch units 22 and 23 includes two dies 36 and punches 54 as is the case of the press machine herein disclosed as one preferred embodiment of the present invention.

FIGS. 38 and 39 illustrate a press line utilizing a plurality of, for example, six continuous rotary presses according to the present invention. In this press line, the first three of the press machines L₁ to L₃ are used to perform drawing in three stages, the subsequent two press machines L₄ and L₅ perform ironing in two stages and the last press machine L₆ perform trimming. A coil of strip stock can be continuously fed from the feed reel R to a scrap box SB through these machines L₁ to L₆ in the sequence give above. The strip stock emerging

from the last stage of the press line, i.e., the press machine L_6 , is successively cut by a suitable cutter into a plurality of scraps which are received in the scrap box.

All of these press machines L_1 to L_6 are driven by the motor M in synchronism with each other.

In the foregoing description of the present invention, the die and punch units 22 and 23 have been described as radially outwardly arranged in the rotary turret 12. However, in principle, it is possible to employ a pair of endless chains or conveyors in place of the rotary turret. In this case, the die and punch units are respectively supported by the endless chains or conveyors which are operated in synchronism with each other so that the die units and the punch units successively cooperate with each other to perform a definite press work. This arrangement should be understood as falling within the concept of the present invention.

Although the present invention has been fully described in connection with the preferred embodiments thereof, it should be noted that various changes and modifications are apparent to those skilled in the art. Such changes and modifications should be understood as included within the scope of the present invention unless they depart therefrom.

What we claim is:

1. A continuous rotary press which comprises in combination:

a rotary turret;

a plurality of first tool units radially arranged with respect to the axis of rotation of said turret and slidably supported by said turret;

second tool units corresponding in number to said first tool units, each mounted in cooperative relation with the corresponding one of said first tool units for performing a definite press work, said second tool units being radially arranged with respect to the axis of rotation of said turret in alignment with said respective first tool units and slidably supported by said turret around and adjacent to the axis of rotation of said turret;

means operatively positioned for rotating said rotary turret in one direction while carrying said first and second tool units;

first means stationarily held by a non-movable portion of the machine body for successively causing said first tool units to alternately move close to and away from the corresponding second tool units during each rotation of said turret;

second means stationarily held by a non-movable portion of the machine body for successively causing said second tool units to alternately move close to and away from the corresponding first tool units during each rotation of said turret, said definite press work being performed as said first tool units and said second tool units undergo relative movement close to each other while said first and second tool units carried by said turret travel around the axis of rotation of said turret;

means operatively positioned for guiding a strip material, which is to be subjected to said definite press work, so as to feed said strip material between said first and second tool units, said strip material being successively held in position between said first and second tool units during the performance of said definite press work with no substantial interruption in the advance thereof; and

stripper means stationarily carried around the axis of rotation of said turret for rotation together therewith, said stripper means having a flat surface, the plane of said flat surface intersecting the direction of movement of any of the corresponding first and second tool units of one pair, said strip material being adapted to be wound around said stripper means so as to be fed therearound substantially without accompanying lengthwise and widthwise displacements.

2. A continuous rotary press as claimed in claim 1, further comprising means for adjusting a relative position of said first and second means.

3. A continuous rotary press as claimed in claim 1, wherein said first tool units and said second tool units respectively include dies and punches and wherein, when said relative movement of said first and second tool units close to each other takes place, said dies and said punches successively engage to each other to perform the definite press work.

4. A continuous rotary press as claimed in claim 3, wherein each one of said dies and punches is specifically designed for a drawing operation.

5. A continuous rotary press as claimed in claim 3, wherein each one of said dies and punches is specifically designed for an ironing operation.

6. A continuous rotary press as claimed in claim 3, wherein each one of said dies and punches is specifically designed for a trimming operation.

7. A continuous rotary press as claimed in claim 1, wherein said guiding means comprises at least one pair of separate guides arranged so as to feed the strip material in a substantially spiral form around the radially arranged second tool units.

8. A continuous rotary press as claimed in claim 1, further comprising means operatively positioned for giving a tension to the strip material between it and said guiding means.

9. A continuous rotary press as claimed in claim 1, further comprising means operatively positioned for positively taking up said strip material from said guide means after the definite press work has been performed.

10. A continuous rotary press system, comprising a plurality of continuous rotary press members, each of said members performing different press operations, a motor synchronously coupled to each of said continuous rotary press members for operation thereof, each of said continuous rotary press members comprised of

a rotary turret;

a plurality of first tool units radially arranged with respect to the axis of rotation of said turret and slidably supported by said turret;

second tool units corresponding in number to said first tool units, each mounted in cooperative relation with the corresponding one of said first tool units for performing a definite press work, said second tool units being radially arranged with respect to the axis of rotation of said turret in alignment with said respective first tool units and slideably supported by said turret around and adjacent to the axis of rotation of said turret;

means operatively positioned for rotating said rotary turret in one direction while carrying said first and second tool units;

first means stationarily held by a non-movable portion of the machine body for successively causing

said first tool units to alternately move close to and away from the corresponding second tool units during each rotation of said turret;
 second means stationarily held by a non-movable portion of the machine body for successively causing said second tool units to alternately move close to and away from the corresponding first tool units during each rotation of said turret, said definite press work being performed as said first tool units and said second tool units undergo relative movement close to each other while said first and second tool units carried by said turret travel around the axis of rotation of said turret;
 means operatively positioned for guiding a strip material which is to be subjected to said definite press work so as to feed said strip material between said first and second tool units, said strip material being successively held in position between said first and second tool units during the performance of said definite press work with no substantial interruption in the advance thereof; and
 stripper means stationarily carried around the axis of rotation of said turret for rotation together therewith, said stripper means having a flat surface, the plane of said flat surface intersecting the direction of movement of any of the corresponding first and second tool units of one pair, said strip material being adapted to be wound around said stripper means so as to be fed therearound substantially without accompanying lengthwise and widthwise displacements.

11. A continuous rotary press which comprises in combination:

a drive shaft adapted to be driven in one direction by a suitable motor;
 a rotary turret mounted on said drive shaft for rotation together with said drive shaft;
 a plurality of first tool carriages radially and circumferentially arranged with respect to and in spaced relation to said drive shaft, each of said first tool carriages being adapted to carry at least one die; second tool carriages corresponding in number to said first tool carriages, each of which is adapted to carry a punch counteracting to said die, said dies of said first tool carriages and said punches of said second tool carriages being in cooperative relation to each other to successively perform a definite press work, said second tool carriages being radially and circumferentially arranged with respect to and in spaced relation to said drive shaft and positioned between said first tool carriages and said drive shaft with said punches respectively aligned with said dies;
 a first annular cam plate having a first continuous cam groove and stationarily held by a non-movable portion of the machine body;
 a second annular cam plate having a second continuous cam groove and stationarily held by a non-movable portion of the machine body;
 first cam followers operatively engaged in said first continuous cam groove;
 second cam followers operatively engaged in said second continuous cam groove;
 first separate means slidably supported by said turret for connecting said first tool carriages to said first cam followers, respectively;

second separate means slidably supported by said turret for connecting said second tool carriage to said second cam followers, respectively, said first and second cam grooves being designed such that, during each rotation of said turret about said drive shaft, said first and second tool carriages successively undergo relative sliding movement in a radial direction close to and away from each other, said definite press work being performed as said first tool carriages and said second tool carriages successively undergo said relative movement close to each other while said first and second tool carriages carried by said turret through said first and second separate means, respectively, travel around said drive shaft;
 means for guiding a strip material, so as to feed said strip material between said first and second tool carriages, said strip material being successively held in position between said first and second tool carriages during the performance of said definite press work with no substantial interruption in the advance thereof; and a plurality of strippers corresponding in number to any of said first and second tool carriages and radially and circumferentially carried by said drive shaft, each of said strippers having a flat portion overhanging a corresponding one of said first tool carriage and the plane of said flat portion intersecting the direction of movement of any of the corresponding die and punch of one pair, said strip material being adapted to be wound around said strippers so as to be fed therearound substantially without accompanying lengthwise and widthwise displacements.

12. A continuous rotary press as claimed in claim 11, further comprising means for adjusting a relative position of said first and second cam plates, said adjusting means being positioned between one of said first and second cam plates and the non-movable portion of the machine body.

13. A continuous rotary press as claimed in claim 11, wherein any one of said first separate means comprises at least one shank slidably supported by the rotary turret and having one end rigidly connected with the corresponding one of the first tool carriages and wherein each of said first cam followers is eccentrically mounted to the other end of said shank for affording adjustment of a relative position of said first tool carriage with respect to the associated second tool carriage.

14. A continuous rotary press as claimed in claim 11, wherein any one of said second separate means comprises at least one shank slidably supported by the rotary turret and having one end rigidly connected with the corresponding one of the second tool carriages and wherein each of said second cam followers is eccentrically mounted to the other end of said shank for affording adjustment of a relative position of said second tool carriage with respect to the associated first tool carriage.

15. A continuous rotary press as claimed in claim 11, wherein said dies and said punches are respectively specifically designed for a drawing operation.

16. A continuous rotary press as claimed in claim 11, wherein said dies and said punches are respectively specifically designed for an ironing operation.

17. A continuous rotary press as claimed in claim 11, wherein said dies and said punches are respectively specifically designed for a trimming operation.

18. A continuous rotary press as claimed in claim 11, wherein said guiding means comprises at least one pair of separate guides arranged so as to feed the strip material in a substantially spiral form round the radially and circumferentially arranged second tool carriages.

19. A continuous rotary press as claimed in claim 12, further comprising means operatively positioned for giving a tension to the strip material between it and said guiding means.

20. A continuous rotary press as claimed in claim 11, further comprising means operatively positioned for positively taking up said strip material from said guiding means after the definite press work has been performed.

21. A continuous rotary press as claimed in claim 11, said second tool carriages includes a corresponding number of stripper plates each being positioned so as to overhang the corresponding one of the second tool carriages and wherein each of the dies passes through said stripper plate when said first and second tool car-

riages relatively move close to each other.

22. A continuous rotary press as claimed in claim 21, wherein each of said stripper plates is formed with an opening and further comprising a sleeve-like member axially collapsibly housed within said opening of said stripper plate, and an elastic member for biasing said sleeve-like member in one direction towards the corresponding first tool carriage for ensuring a tight contact of the strip material between the strip plate and the corresponding first tool carriage.

23. A continuous rotary press as claimed in claim 11, further comprising means operatively positioned for ejecting articles formed by the definite press work from the strip material under the influence of centrifugal force generated during rotation of the rotary turret.

24. A continuous rotary press as claimed in claim 11, wherein each of said first tool carriages includes a depressor for depressing the strip material towards the corresponding second tool carriage for avoiding formation of wrinkles during the performance of the definite press work.
